Spec. 3.

Patented Aug. 25, 1925.

UNITED STATES PATENT OFFICE.

ARTHUR S. OLSON, OF MURDOCK, MINNESOTA.

SNOW-CLEANING APPARATUS.

Application filed February 11, 1925. Serial No. 8,474.

To all whom it may concern:

Be it known that I, ARTHUR S. OLSON, a citizen of the United States, residing at Murdock, in the county of Swift and State 5 of Minnesota, have invented certain new and useful Improvements in a Snow-Cleaning Apparatus, of which the following is a specification.

The present invention relates to a machine for cleaning snow from streets, roadways, and the like, and aims to provide a structure which is capable of being incorporated on a truck chassis so that the truck may be driven along the street, roadway or 15 the like, and the snow picked up from in front of the truck and conveyed to the side thereof.

Another important object of the invention is to provide a pair of collecting conveyors 20 which may be adjusted to the desired height and which may be lifted to an inoperative position.

Another important object of the invention is to provide in combination with the 25 collecting conveyors a pair of beaters for breaking up the snow as it is being picked up by the conveyors, and further the provision of means whereby these beaters may be adjusted in relation to the conveyors.

30 A still further important object of the invention is to provide an apparatus of this nature which is comparatively simple and efficient structure which may be readily assembled upon a conventional type of truck, one which is readily assembled or disassembled, strong, durable, not liable to readily get out of order, and otherwise well adapted for the purpose for which it is 35 designed.

40 With the above and numerous other objects in view as will appear as the description proceeds, the invention resides in certain novel features of construction, and in the combination and arrangement of parts 45 as will be hereinafter more fully described and claimed.

In the drawings:

Figure 1 is a top plan view of the apparatus embodying the features of my invention,

50 Figure 2 is a side elevation thereof,

Figure 3 is a transverse section taken vertically therethrough and looking rearwardly,

Figure 4 is an enlarged detail section 55 taken substantially on the line 4-4 of Fig-

ure 2 looking in the direction of the arrow, and

Figure 5 is an enlarged detail view of the 60 crank and ratchet mechanism associated therewith for lifting the beaters.

Referring to the drawing in detail it will be seen that I have illustrated a conventional form of automobile truck, but of course, any other wheeled vehicle could be substituted therefor. In the vehicle which I 65 have illustrated, the numeral 5 designates the chassis thereof on which is mounted uprights 6 by means of cross bars 7, said uprights 6 being of an inverted V-shaped formation in the present instance. The 70 apexes or upper ends of these uprights 6 form journals for receiving pins 8 for pivotally supporting brackets 9 which in turn support collecting conveyors indicated generally by the letter A. As is shown to advantage in Figure 1 there is a pair of these collecting conveyors A which converge toward their front ends into scoops 11. Each conveyor A includes a pair of spaced vertically extending side walls 12 having the endless conveyor 13 operable therebetween. The body of this endless conveyor 13 has extending transversely thereof cleats 14. Chains 15 are engaged with the edges of the body and with the ends of the cleats and are 75 trained over sprockets 16 on the end shafts 17 as is shown to advantage in Figure 2.

An inverted U-shaped frame 19 has its ends fixed to the inner side walls of the conveyors A by means of bolts 20 or in 90 any other suitable manner. A pair of bars 21 and 22 rise from the intermediate portion of the frame 19 and the bar 22 is a rack bar having its teeth 23 on the inner edge thereof. A standard 24 rises from the forward end of the chassis 5 and a shaft 25 is journaled in the upper end thereof and in a suitable bracket 26 at the dash board of the truck. A crank 27 is provided on the end of the shaft 25 at the dash board and 100 a ratchet mechanism 28 is associated therewith as is shown to advantage in Figure 105 5. A pinion 29 rotates with the shaft 25 and meshes with the teeth 23 of the rack bar 22 so that by turning the crank 27 the forward ends of the conveyors A and the scoops 11 may be raised and lowered as desired.

At the rear of the chassis 5 there is 110 mounted a suitable source of power, which

I have shown in the present instance merely by way of example as an electric motor 30. A chain 31 is driven by this prime mover 30 and operates a shaft 32 which extends longitudinally of the rear portion of the chassis being journaled under the conveyor B which will be described later. A beveled gear 33 meshes with a beveled gear 34 on the transversely extending shaft 35 which is journaled in standards 36. Shafts 37 are connected to this shaft 35 by suitable universal joints 38 and is provided with sprockets 39 for driving the chains 15 of conveyors A. These shafts 37 are journaled in brackets 40 on the bottom of the conveyors A. When the motor 30 is in operation it will be seen that the chains 15 and cleats 14 will travel upwardly over the bottom 13 of each conveyor 20 A for delivering snow collected on the scoops 11 to the upper ends of the conveyors for dumping said snow onto the conveyor B.

A frame 44 rises from the forward end 25 of each conveyor A and the sides thereof are slotted as at 45. A shaft 46 is slidable through these slots 45 and carries a beater 47 which includes a plurality of radiating blades as is evident from an inspection of 30 Figure 2. Cables 48 are connected to journal blocks 49 at the outer ends of the shafts 46 and are trained over pulleys 50 at the upper ends of the frames 44. These cables 48 are connected to a common cable 51 35 which is attached to a winding drum 52 having an operating crank 53. By operation of this crank 53 to wind the cable 51 on the drum 52 it will be seen that the beaters 47 may be raised and lowered in respect to the conveyors A. The inner ends of the shafts 46 are provided with sprockets over which are trained chains 55 which extend rearwardly and are trained over 40 sprockets carried by shafts 56 having universal joints 57 and 58 therein and driven by shaft 59. A bevel gear 60 is mounted on the shaft 59 and meshes with a beveled gear 61 on shaft 62 journaled in standards 63 and driven by chains 64 from the prime 45 mover 30. A clutch mechanism 65 is incorporated in the shaft 62 and is operable from adjacent the driver's seat by member 66 or in any other suitable manner. It will thus be seen that the conveyors A may be 50 operated independently of the beaters 47 as may be desirable, especially when the snow is rather light and there is no necessity of breaking it up.

The conveyor B extends transversely of 55 the chassis and is mounted on the standards 70 so as to be located below the delivery or upper ends of the conveyors A. This conveyor B includes the side walls 71 and 72, the latter being slanted rearwardly and the bottom 73 over which travel the cleats 74

carried by chains 75 trained over sprockets in the end shafts 76 journaled in brackets 77 depending from the sides 71 and 72. The shaft 32 which is driven from the prime mover 30 by chains 31 is provided with a pair of sprockets 78 indicated in dotted lines in Figure 1 which mesh with the chains 75 for driving the conveyor B so that snow will be delivered to the right of the chassis. 75

It will be apparent from the above detailed description that this apparatus will collect the snow in front of the vehicle as the latter is traveling forwardly. This snow will be collected on the scrapers 11, 80 broken up by the beaters 47 and delivered by the conveyors A to the conveyor B. This conveyor B will pile the snow collected to the right of the vehicle. It will further be apparent that the conveyors A may be lifted to an out-of-the-way position when desired and may be also adjusted in relation to the ground as may be desired by operation of the crank 27. Further, it is to be noted that the beaters 47 may be adjusted in relation to the conveyors A as will be desired depending upon the depth of the snow and when these beaters are not necessary they may be lifted to the upper ends of the slots 45 and the clutch 65 opened so that the conveyors will no longer operate. It is thought that the construction and operation of the invention will now be clearly understood without a more detailed description thereof, but it is desired to point out numerous changes in the details of construction, and in the combination and arrangement of parts may be resorted to without departing from the spirit or scope of the invention as hereinafter claimed and without sacrificing any of its advantages. 95 100 105

Having thus described the invention, what I claim as new is:—

1. In combination, a vehicle, a conveyor mechanism rockably mounted on the vehicle 110 to extend longitudinally thereof, a frame attached to the forward end of the conveyor mechanism, a rack bar attached to the frame, a shaft journaled longitudinally of the vehicle, means for operating the shaft, a pinion on the shaft meshing with the rack bar for raising the forward end of the conveyor mechanism.

2. In combination, a vehicle, a conveyor mechanism rockably mounted on the vehicle, 115 means for adjusting the conveyor mechanism in relation to the vehicle, a frame including slotted uprights mounted on the forward end of the conveyor mechanism, shafts 120 slidable and rotatable in the slotted uprights, beaters on the shafts, and means for lowering and raising the beaters. 125

3. In combination, a vehicle, a pair of conveyor mechanisms mounted longitudinally of the vehicle for collecting snow at 130

the forward end of the vehicle and delivering it to an intermediate portion of the vehicle, said conveyor mechanisms being rockably mounted adjacent their rear ends on 5 the vehicle, a third conveyor mounted transversely of the vehicle immediately below the delivery ends of the first mentioned conveyor mechanisms for delivering the snow to one side of the vehicle, means for operating the 10 conveyor mechanisms, a frame attached to the forward ends of the longitudinally extending and rockably mounted conveyor mechanisms, a rack bar fixed to the frame, a

shaft extending longitudinally of the vehicle, a pinion on the shaft meshing with 15 the rack bar, means for rotating the shaft whereby the forward ends of the rockably mounted conveyors may be raised or lowered, slotted uprights on the forward ends 20 of the conveyors, beaters having shafts slideable and rotatable in said slotted uprights, means for rotating the beaters, and means for raising and lowering the beaters.

In testimony whereof I affix my signature.

ARTHUR S. OLSON.
